PUMP

Melmoth W. Hunter, Lorain, Ohio

Application November 20, 1933, Serial No. 698,831

14 Claims. (Cl. 103—118)

This invention relates to improvements in pumps and while adapted for use generally wherever it may be advantageously employed, the invention is particularly intended for application to pumps for circulating water in the cooling systems of internal combustion engines in which connection it will be illustrated in the drawings and hereinafter described.

Objects of the invention are to provide a pump of simple, durable construction which can be manufactured at a low cost and which will include a completely enclosed pump casing having an axial inlet opening and having a wabbler element centrally mounted therein for limited tipping movement in every direction and to provide magnetic means for tipping the same in continuous, circumferential progression whereby water within the casing will be given a rapid whirling motion sufficient to cause it to be centrifugally expelled through a discharge opening in the peripheral wall of said casing, and to provide a casing having a magnetically attractive wall and a non-magnetic diaphragm forming an opposed wall, said walls provided with axially aligned, opposed annular seats which form bearing surfaces which progressively engage the peripheral portions of said wabbler element and which limit the wabbling movement thereof.

A particular object is to provide a centrifugal pump having a magnetically attractive impelling element which will impart a rapid whirling movement to a liquid by a circumferentially progressing tipping movement instead of the usual rotary movement and to completely enclose said impelling element and provide magnetic means for providing such tipping movement of the impelling element and to thereby provide an efficient pump having no packing glands and having an impelling element which may be operated continuously for a long period of time without lubrication and without being materially effected by wear.

A further object is to provide a practical, centrifugal pump having a casing enclosing a pump cavity with the impelling element therein and to enclose said casing with a non-magnetic diaphragm and to provide a fixed solenoid having a rotatable core terminating in an end portion forming a permanent magnet inclined from the axis of the core toward a peripheral portion of the impelling element and to provide means for rotating said core to cause a circumferentially progressive tipping movement of said impelling element and to thereby provide a flow of magnetic flux in an annular path coincident with

the peripheral portions of said impelling element, without the use of brushes or other movable connections and to provide a pump in which a liquid may be congealed by freezing or otherwise and which will not be broken by operating the driving means while the liquid is so congealed.

A still further object is to provide a pump of the character above indicated which may be operated by making, breaking or otherwise controlling the electrical circuit in which the electro-magnet is interposed, either manually, thermostatically or otherwise.

Other objects will be made apparent by the following specification in which a specific adaptation of the invention will be described with reference to the illustrative embodiment thereof disclosed in the drawings, it being understood that changes and modifications may be made which come within the spirit of the invention as set forth in the appended claims:

In the drawings:—

Figure 1 is a side elevational view of a portion of an internal combustion engine equipped with a pump constructed in accordance with this invention,

Figure 2 is a central, vertical, longitudinal view of a pump constructed in accordance with this invention,

Figure 3 is a cross sectional view taken as indicated by the lines 3—3 of Figure 2 with the wabbler element removed.

Figure 4 is a plan view of the interior face of the non-magnetic diaphragm employed in reducing the invention to practice.

Figure 5 is a plan view of the impelling element employed in the adaptation of the invention illustrated.

Proceeding now to a detailed description of the illustrated adaptation of the invention, the numeral 6 is employed to designate a motor block of an internal combustion engine and the numeral 7 the motor head. The head 7 and the block 6 are provided with the usual water cavity 8. The numeral 9 denotes a pump casing which forms an integral part of the head 7 and projects forwardly therefrom. The forward wall 10 of the head 7 forms the rear wall of the pump cavity 11. The pump cavity 11 is of convolute form, its peripheral wall forming a single convolution, and is provided on the rear wall 10 with a centrally positioned, cylindrical passage 12 which communicates with the water cavity 8.

The numeral 13 denotes an outlet nipple which projects upwardly from the upper side of the pump casing 9. The bore 14 of the nipple 13

leads from the outermost portion of the convoluted wall and communicates with the cavity 11. The wall of the pump casing 9 is relatively thicker at one side of the bore 14 and the cavity 11 gradually enlarges to provide a greater diameter at the opposite side of the bore 14. The wall of the bore 14 curves at the inner end thereof toward the enlarged side of the cavity 11 thus terminating at the thickened portion of the wall 10 9 at a sharp angle to the circumferential wall of the cavity, while the opposite side of the wall of the bore 14 forms a continuous curved line which is in fact a continuation of the wall of the cavity. The wall 10 is thickened around the opening 12 on the forwardly presented side thereof to provide an annular seat 15 which is in the form of a truncated cone with the bore 12 in the exact center thereof. The casing 9 is provided with an enlarged opening 16 on the forward side thereof, the opening 16 being further enlarged to provide a seat 17 in which is mounted a diaphragm 18 which completely closes the opening 16, a suitable gasket 19 being employed to seal the joint between the diaphragm 18 and the seat 17.

The numeral 20 denotes a magnet casing which is closed at the outer end and is provided at the inner end thereof with a face adapted to fit against the forward wall of the casing 9 and against the peripheral portions of the diaphragm 18. The magnet casing 20 is secured to the pump casing 9 by means of the bolts 21 or other suitable means. The magnet casing 20 is provided with a rearwardly presented annular cavity 22 in which is operatively mounted a solenoid consisting of a coil or coils 23, and the central portion 24 of the magnet casing 20 projects rearwardly in the form of a cylinder and is provided with an axial bore which forms a bearing for the shaft 25.

The diaphragm 18 is composed of brass or other non-magnetic material and the main body thereof is disposed in parallel relation with the main portion of the wall 10. The diaphragm 18 has a relatively thin central portion which is pressed rearwardly to provide the annular seat 18a which is in the form of a truncated cone and which is directly opposed to the annular seat 15. The seat 18a is arranged in co-axial alignment with the seat 15 and in the particular adaptation of the invention shown, said seats form conical surfaces, every portion of which is in alignment with the surface of the other seat, diametrically opposite thereto.

The numeral 26 denotes a wabbler element which is in the form of a disk having a central opening 27 and provided adjacent the center thereof with a plurality of openings 28. The numeral 29 denotes a pin which is suitably secured to the central portion of the diaphragm 18 so as to project therefrom. The wabbler element 26 is positioned in the cavity 11 with the pin 29 loosely received in the opening 27 in a position where the marginal portion of one side thereof will fit against a portion of the seat 15 at one side thereof and the diametrically opposed marginal portion of the other side of the disk will fit against the seat 18a, thus mounting the wabbler element 26 for tipping movement across the cavity in every direction, this tipping movement being limited only by the seats 15 and 18a.

In the particular adaptation of the invention shown, the peripheral portion of the wabbler element 26 tapers outwardly to a relatively thick edge portion. The pin 29 is provided at the forward end thereof with a rounded base 31 and

at the rear end thereof with a head 30 which functions to retain the wabbler element 26 in a central portion in the cavity 11 and which will prevent the wabbler element 26 from being drawn flat against either side of the cavity 18. Means are then provided for moving the wabbler 26 to an operative position. The central portion 24 of the magnet casing 20 terminates in spaced relation to the rear end of the casing. A portion of the shaft 25 is enlarged to form a shoulder 32 which fits against the rear end of the central portion 24.

The rear end portion 25a of the shaft 25 projects rearwardly from the shoulder 32 at an inclination to the axis thereof. The portion 25a terminates in close, spaced relation to the diaphragm 18 whereby the rearwardly presented face thereof will always be positioned directly in front of some portion of the seat 18a. The casing 20 and the central portion thereof 24 is composed of iron or other material which is a good conductor of magnetic flux. The shaft 25 or at least the end portion 25a is composed of steel whereby it may be energized by the operation of the coil 23 to form a permanent magnet. The shaft 25 projects forwardly from the casing 20 and is provided with a drive sheave 33 which is fixedly secured thereto by means of the set screw 34 or other suitable means. In the particular adaptation of the invention, the shaft 25 is provided on the forward end thereof with a fan 35 which is suitably fixed thereto.

The diaphragm 18 is composed of brass or other non-magnetic material while the walls of the casing 9 are composed of iron or other material which is a good conductor of magnetic flux.

In operation, the coil 23 is energized by operatively connecting it to a source of electrical energy. As the rearwardly presented portion 25a of the shaft 25 is presented toward a portion of the seat 18a, one side of the wabbler element 26 will be drawn against the seat 18a, while the side of the wabbler element 26 diametrically opposite will be drawn flat against the opposite side of the seat 15. As the shaft 25 is rotated by means of the belt 36, the rearwardly presented end portion 25a of the shaft 25 travels in an annular path which is coincident with the seat 18a. The wabbler element 26 will be continuously tipped in circumferential progression in the cavity 11, thus providing a rapid whirling motion of the liquid within the cavity 11. This whirling motion expels the liquid through the nipple 13 to the tube 37 which operatively connects the nipple 13 with a radiator 38.

It will be seen that the magnetic flux generated by the coil 33 will flow forwardly through the end portion 25a and through the diaphragm 18a to the peripheral portion of the wabbler element 26 and will flow through the wabbler element 26 to the wall 10 whereupon it will flow through the wall 20 thus completing the magnetic circuit. As the wabbler element 26 is provided with an opening 28, the water thus expelled through the nipple 13 will be replaced by water drawn through the bore 12. The opening 28 acts to permit the inlet flow of liquid to both sides of the wabbler element 26.

While I have described the laterally diverted pole piece 25a as composed of steel to form a permanent magnet, it is understood that the same may be composed of iron or other suitable material which will not be permanently magnetized. The coil 23 may be in the form of one, two or any number of coils, wound in accordance with the result desired. An additional coil may be sub-

stituted to form an electro-magnet which will function as the permanent magnet formed by the pole piece 25a or the coil 23 may be formed of individual windings adapted to be selectively employed to produce the desired pumping action.

The flow of electrical current to the coil 22 or to one or more coils composing same may be thermostatically controlled to produce any desired operation of the propeller element, it being thus possible to bring the wobbling movement of the impeller element into synchronism with the rotary pole piece 25a or to produce a slower movement thereof. A thermostatic control may be employed to disconnect the coil or coils 23 when the temperature of the motor is below a certain point.

Having thus illustrated my invention, what I claim as new and desire to secure by Letters Patent is:—

1. In a pump of the character described, a suitable casing enclosing an unobstructed chamber extending continuously between the walls thereof, said chamber having an axial inlet opening and a peripheral discharge opening, an impeller mounted therein for tilting movement in every direction and means to progressively tilt said impeller in continuous, circumferential progression.

2. In a pump of the character described, a suitable casing having side walls with a pump chamber extending continuously therebetween, one of said side walls having a centrally positioned inlet opening leading to the central portion of said chamber; said chamber having a peripheral discharge opening leading from said chamber, a disk mounted therein for tilting movement across the cavity of the casing in every direction and means to progressively tilt said disk in continuous, circumferential progression.

3. In a pump of the character described, a suitable casing enclosing a continuous pump chamber, said chamber having a central inlet opening and a discharge opening positioned radially outwardly with respect to said inlet opening, an impeller fulcrumed therein for tilting movement in every direction and means outside of said casing to progressively tilt said disk in continuous, circumferential progression.

4. In a pump of the character described, a casing having opposed side walls and a peripheral wall enclosing an unpartitioned chamber, a disk loosely fulcrumed in said casing for tipping movement in every direction, said casing provided with an inlet opening leading to the central portion of said chamber and having a discharge opening leading from said chamber and positioned radially outwardly with respect to said inlet opening and magnetic means operable to tip said disk in continuous, circumferential progression.

5. In a pump of the character described, a casing having oppositely disposed side walls of like contour, extending in the same general direction and a peripheral wall enclosing an unobstructed cavity, a disk positioned in said casing for tipping movement in any direction to bridge the space between said walls, said casing provided with an inlet port leading to the central portion of said cavity and having a discharge opening leading from said cavity at a point spaced outwardly from the center thereof and means to tip said disk in continuous, circumferential progression.

6. In a pump of the character described, a casing having opposed side walls, and a peripheral wall enclosing an unobstructed cavity, a disk positioned in said casing for tipping movement in every direction to extend between said walls,

said chamber provided with a centrally positioned inlet opening and a discharge opening positioned radially outwardly with respect to said inlet opening, said side walls provided with opposed, axially aligned seats concentrically arranged around the axis of the pump, the diametrically opposed marginal portions of said disk adapted to bear against said seats, and means to rapidly tip said disk in continuous, circumferential progression.

7. In a pump of the character described, a casing having a cavity with oppositely disposed, similar side walls and a convolute peripheral wall, said casing having an inlet opening in one side wall thereof leading to the central portion of said cavity and a discharge opening in the peripheral wall thereof leading from said cavity, a circular impeller element fulcrumed on an extended axis of said inlet opening for tilting movement in every direction, said impeller element being of sufficient diameter to simultaneously contact at an acute angle with both side walls and means operable to progressively tilt said impeller element in continuous, circumferential progression.

8. In a pump of the character described, a casing having a cavity with oppositely disposed side walls of similar contour and a peripheral wall enclosing an unpartitioned cavity, said casing having an inlet opening leading to the central portion of said cavity and a discharge opening leading from said cavity at a point spaced radially outwardly with respect to said inlet opening, a circular impeller element mounted in said casing for tilting movement in every direction, said impeller element being of sufficient diameter to simultaneously contact with both side walls, said impeller element provided with an opening in the central portion thereof and means operable to progressively tilt said impeller element in continuous, circumferential progression.

9. In a pump of the character described, a casing having a cavity with oppositely disposed side walls of similar contour and a peripheral wall, said walls enclosing an unobstructed cavity, said casing having an inlet opening in one side wall thereof leading to the central portion of said cavity and a discharge opening leading from a peripheral portion of said cavity; a circular impeller element in said casing, said impeller element loosely fulcrumed on an extended axis of said inlet opening for tilting movement in every direction, said impeller element being of sufficient diameter to simultaneously contact with both side walls, an annular seat on each side for contacting with the marginal portion of said impeller element and magnetic means operable to progressively tilt said impeller element in continuous, circumferential progression.

10. In a pump, a casing composed mainly of magnetically conductive material, said casing having side walls and a peripheral wall, said casing having an inlet opening in one side wall thereof and having a discharge opening in the peripheral wall thereof, the forward wall of said casing being in the form of a relatively thin diaphragm of non-magnetic material, a disk positioned in said casing, said disk adapted to be tilted across the cavity of said casing with one edge portion contacting with the rear wall thereof and the diametrically opposite edge portion contacting with said diaphragm, an electromagnet having a rotatable core connected to said casing, the said core terminating in an inclined pole portion presented to the outer face of said

- diaphragm and adapted when rotated to travel in an annular path coincident with the peripheral edge of said disk and means to rotate said core and tilt said disk in continuous, circumferential progression.
11. In a pump, a casing composed mainly of magnetically conductive material, said casing having parallel side walls and a peripheral wall, said casing having an inlet opening in one side wall thereof and having a discharge opening in the peripheral wall thereof, the forward wall of said casing being in the form of a relatively thin diaphragm of non-magnetic material, opposed, axially aligned, annular seats on the inner faces of said side walls, a disk of magnetically conductive material positioned in said casing, said disk adapted to be tilted across the cavity of the casing with opposite edges thereof simultaneously contacting with said seats, an electric magnet having a rotatable core connected to said casing, said core terminating in an inclined pole portion presented to the outer face of said diaphragm and adapted when rotated to travel in an annular path coincident with the peripheral edge of said disk thereby interposing said disk in the field of said magnet and means to rapidly rotate said core and tilt said disk in continuous, circumferential progression.
12. In a pump, a casing composed of magnetically conductive material, said casing having substantially parallel side walls and a peripheral wall, said casing having a centrally positioned inlet opening in one side wall thereof and having a suitable discharge opening, one wall of said casing being relatively thin and composed of magnetically non-conductive material, opposed, axially aligned, conical seats on said side walls, a disk positioned in said casing, with one edge portion thereof bearing against one of said seats and the diametrically opposed edge portion thereof bearing against the other seat, an electric magnet frame composed of magnetic conductive material operatively connected to said casing,
- 5 a magnet coil in said frame, a suitable core rotatably mounted on said frame and extending through said coil, the said core terminating in a diverted pole portion presented in close spaced relation to the outer face of said thin side wall and adapted when rotated to travel in an annular path coincident with the seat on said thin side wall, said disk being thus interposed in the magnetic circuit of said coil, means to energize said coil and means to rapidly rotate said core to cause 10 a continuous, circumferentially progressing tilting movement of said disk.
13. In a pump, a casing composed of magnetically conductive material, said casing having substantially parallel side walls and a peripheral wall, said casing having a centrally positioned inlet opening in one side wall thereof and having a suitable discharge opening, one wall of said casing being relatively thin and composed of magnetically non-conductive material; opposed, 20 axially aligned, conical seats on said side walls, a disk positioned in said casing, with one edge portion thereof bearing against one of said seats and the diametrically opposed edge portion thereof bearing against the other seat, an electric mag- 25 net frame composed of magnetic conductive material operatively connected to said casing, a solenoid coil fixed in said frame, a rotatably mounted core for said solenoid, said core project- 30 ing rearwardly from said coil and terminating in an end portion diverted from the axis of the sole- noid with the end thereof close to said diaphragm and adapted when rotated to cause an operative movement of said wabbler element.
14. In a pump of the character described, a 35 casing having a wabbler element mounted therein for continuous, circumferential tipping movement, a solenoid coil fixed in coaxial alignment therewith, a core rotatably mounted in said coil, said core having a diverted end portion positioned 40 to influence said wabbler element and means to rotate said core.

MELMOTH W. HUNTER.
